UNITED STATES PATENT OFFICE.

FRANK L. HARMON, OF BEVERLY, MASSACHUSETTS, ASSIGNOR TO UNITED SHOE MACHINERY COMPANY, OF PATERSON, NEW JERSEY, A CORPORATION OF NEW JERSEY.

BUTTONHOLE-PIECE.

1,076,764.

Specification of Letters Patent.

Patented Oct. 28, 1913.

Application filed February 29, 1912. Serial No. 680,650.

To all whom it may concern:

Be it known that I, FRANK L. HARMON, a citizen of the United States, residing at Beverly, in the county of Essex and State of Massachusetts, have invented certain Improvements in Buttonhole-Pieces, of which the following description, in connection with the accompanying drawings, is a specification, like reference characters on the drawings indicating like parts in the several figures.

This invention relates to an improved buttonhole piece and more particularly to means for finishing and reinforcing the edge of a buttonhole.

It has been customary heretofore to reinforce buttonholes by laying a stay cord upon the inside of the buttonhole piece or fly close to the edge of the buttonhole and binding it to the base material with stitches which pass over it and over the edge of the buttonhole, thus inclosing the cord without passing through it. It is customary thereafter to "finish" the buttonhole piece by whipping down or stitching the stay cord and thrums, extending between the ends of adjacent buttonholes, to the base material. This finishing operation is intended to prevent the stay cord from slipping under the stitches when stress is exerted by the button upon the buttonhole and also secures the cord and thrums in place.

In accordance with the present invention the buttonhole piece is provided with a reinforcing strip or cord which is laid in place in the usual way and secured to the base material by the usual "buttonhole stitches," except that these stitches not only bind the edge of the buttonhole but also pass through the cord instead of over it, thereby making a much stronger and more durable buttonhole since the cord is firmly held in place and prevented from slipping under the stitches when the buttonhole is subjected to strain.

It is believed that in making a buttonhole piece according to the present invention the finishing operation will be unnecessary, since the cord at the inner end of the buttonhole is securely sewed to the material and hence, that portion of the stay cord and the thrums between adjacent buttonholes may be cut away, if desired, so that the completed buttonhole piece will be not only stronger but also neater in appearance and, in fact, better

"finished" than a buttonhole in which the stay cord and thrums are whipped down by blind stitching in the customary manner.

Referring to the accompanying drawings, Figure 1 is a plan view of a portion of the inner side of a buttonhole piece for boots and shoes embodying the present invention in its preferred form; Fig. 2 is a vertical cross section on the lines 1-1 of Fig. 1, and Fig. 3 is an enlarged perspective view of one of the buttonholes.

The drawings represent a buttonhole piece for a boot or shoe, comprising a base material 2 having buttonholes 4, 5 and 6. The reinforcing strip or cord 8 is laid upon the inside of the buttonhole piece close to the edge of the buttonholes with one edge of the cord substantially in alignment with the edge of the hole. This cord is secured to the base material 2 by the overstitching, i. e. by buttonhole stitches 10 which pass through the cord 8 near its outer edge, and through the base material 2 and then over the inner edges of the cord and hole, so as to bind and finish the edge of the hole in the usual manner. The cord 8 crosses over itself as at 12 and extends to the next adjacent buttonhole. The overstitching is carried across the inner end of the buttonhole to unite the crossed portions of the cord firmly to each other and to material of the base.

With the cord sewed directly to the material as described, the portion 14 of the cord 8 extending between the adjacent buttonholes, as well as the thrums, may be cut away, if desired, without weakening the buttonhole, as illustrated for one buttonhole at 16, Fig. 1. This renders the usual finishing operation unnecessary, as already suggested above.

The various usual forms of stay cord or tape can be utilized in carrying out the present invention but it is deemed preferable to employ a substantially non-stretching reinforcing cord which is normally circular in cross section but which will flatten out under the tension of the stitches so as to leave no objectionable ridge on the finished buttonhole piece although conforming to and lying substantially flat around the outer end of the buttonhole.

Having thus described my invention, what I claim as new and desire to secure by Letters Patent of the United States is:

1. A buttonhole piece comprising a base

- material provided with a buttonhole, in combination with a reinforcing strip around the edge of the buttonhole and a series of stitches securing the strip to the base material passing through both the strip and the base material and also over the edge of the hole.
2. A buttonhole piece comprising a base material provided with a series of buttonholes in combination with a reinforcing cord 10 laid around the edge of each buttonhole with one of the edges of the cord substantially in alinement with the edge of the hole, said cord having a width substantially greater than its thickness, and a series of stitches 15 passing through both the base material and the cord and also over the edge of the hole whereby said stitches serve both to bind and finish the edge of the hole and also to secure the cord firmly to the base material.
- 20 3. A buttonhole piece comprising a base material provided with a series of buttonholes in combination with a reinforcing strip around the edge of each buttonhole and terminating adjacent the inner end of the buttonhole and a series of stitches securing the strip to the base material passing through

both the strip and the base material and also over the edge of the hole.

4. A buttonhole piece comprising a base material 2 provided with a series of buttonholes in combination with a relatively flat reinforcing strip 8, lying upon the unexposed face of said material and extending entirely around the edge of each buttonhole with one of its edges substantially in alinement with the edge of the hole and crossing over itself at the inner end of the hole, and a series of stitches 10 passing through both the strip and the base material 2 and also over the edge of the hole, including the edge 40 at the inner end of the hole so as to unite the crossed portions 12 of the strip 8 firmly to each other and to the base material 2, substantially as described.

In testimony whereof I have signed my 45 name to this specification in the presence of two subscribing witnesses.

FRANK L. HARMON.
